UNITED STATES PATENT OFFICE.

KICHIZO NARAHARA, OF ALAMEDA, CALIFORNIA.

SASH HOLDER AND LOCK.

974,696.

Specification of Letters Patent.

Patented Nov. 1, 1910.

Application filed November 11, 1909. Serial No. 527,539.

To all whom it may concern:

Be it known that I, KICHIZO NARAHARA, a subject of Japan, residing at Alameda, in the county of Alameda and State of California, have invented certain new and useful Improvements in Sash Holders and Locks, of which the following is a specification.

This invention relates to combined sash 10 holders and locks, and the principal object of the same is to provide means whereby the upper and the lower sash of a window may be supported in an open position and also means for locking said sashes in either an open or 15 a closed position so that the sashes cannot be operated until the lock is released.

In carrying out the objects of the invention it is contemplated providing a combined 20 holder and lock that may be set in one side of a window casing and provided with oppositely projecting pivotally mounted holding arms for engaging with racks of the usual window sashes, said racks being provided with regularly spaced side catches with 25 which locking fingers may be engaged to prevent movement of the sashes, said arms and fingers being operated from a common shaft on which cam mechanism is mounted for first operating the holding arms to cause 30 them to engage with the racks and then operating the fingers to cause them to engage with the side catches.

In the practical application of the invention it will be understood, of course, that the 35 essential features thereof are necessarily susceptible of changes in details and structural arrangements, one preferred and practical embodiment of which is shown in the accompanying drawings, wherein:—

40 Figure 1 is a fragmentary view in front elevation of a window sash and casing, showing the application of the present invention. Fig. 2 is a similar view, the sash casing being broken away to show the improved holder 45 and lock and the racks carried by the window sashes. Fig. 3 is a detail fragmentary view in front elevation of one side of the window casing showing the holder and lock applied thereto. Fig. 4 is a view in side 50 elevation of the holder and lock. Fig. 5 is a similar view shown partly in section. Fig. 55 6 is a horizontal sectional view taken on the line $\alpha-\alpha$, Fig. 4. Figs. 7 and 8 are detail fragmentary views of sash racks for the upper and lower sashes.

Referring to said drawings by numerals, 1 designates one of the vertical sides of a window casing the front face of which is provided with the vertical grooves 2—3 for the upper and lower window sash. Said casing 60 member 1 has a frame 4 of the improved holder and lock seated therein with its front end plate 5 flush with the front surface of said member. Said end plate 5 is preferably in the form of a circular disk and is 65 provided with two slots 6—7, one slot being in groove 2 and the other slot being in the groove 3 and each slot having an enlarged inner end. Slot 6 extends downward from the center of the disk and slot 7 extends upward from the center of the disk. 70

The frame 4 has the sides of its inner end portion open, each open portion being spanned by a bearing plate 8 in which the horizontal shaft 9 is rotatably mounted, one 75 end of said shaft projecting through one side of the member 1 and being equipped with a knob or finger grip 10 by means of which said shaft may be readily manually operated. The shaft 9 has two cams 11—12 80 fast thereon, said cams being arranged at right angles to one another. Cam 11 is loosely surrounded by the elliptically slotted end 13 of an arm 14, the other end of said arm 14 being equipped with an angular end 85 plate 15 which is provided with locking fingers 16—16^a that are projected through the enlarged inner ends of slots 6—7 by a rotation of shaft 9 to cause cam 11 to engage with the elliptical slot in the end 13 and 90 slide the arm 14 within frame 4.

The end plate 15 has a guide opening 17 formed through it to one side of the arm 14 through which arm 18 is slidable, said arm 18 having its inner end provided with an elliptical slot 19 that loosely surrounds cam 12. The outer end of arm 18 projects beyond member 15 and carries a similar angular end plate 20, each end of which is equipped with a guide opening 21 for the 100 locking fingers 16 and 16^a. The front surface of plate 20 is provided with spaced apart pivot ears 22, in which one end of the holding fingers 23—24 are pivotally mounted, the free ends of said fingers projecting 105 through their respective slots 6—7, the finger 23 projecting upward and the finger 24 projecting downward. Each of said fingers 23—24 have a spring connection 25 with plate 20, said springs being of the expansion 110

type and constantly exerting a pressure tending to force the fingers through their slots 6-7.

It is preferred to use the improved holder

- 5 and lock in connection with the types of sash racks shown in Figs. 7 and 8, the rack shown in Fig. 7 being for use in connection with a lower sash and the one shown in Fig. 8 being for use in connection with an upper 10 sash. The lower sash rack 26 has its teeth 27 on a downward incline, and are adapted to be engaged by the holding finger 23. Said rack has regularly spaced laterally projecting side catches 28, which correspond in number to the teeth 27, said catches being adapted for locking engagement with the finger 16.

The upper sash rack 29 is similarly equipped with teeth 30 and side catches 31, said teeth 20 being obviously arranged in a reverse manner to that of the teeth 27, and adapted for engagement with the finger 24, the catches 31 being adapted for locking engagement with the finger 16^a.

25 From the foregoing it will be seen that by rotating shaft 9, cam 12 will force arm 18 outward and cause the holding fingers 23-23 to engage with the teeth 27-31 of the racks 26-29, which engagement obviously holds the window sashes open. A continuation of the rotation of shaft 9 will cause cam 11 to force arm 14 outward so that locking fingers 16-16^a will engage the side catches of racks 26-29, and thereby 35 prevent movement of either sash.

It will be understood, of course, that the preferred location of the improved holder and lock is adjacent the mid-rail meeting point of the two sashes.

40 What I claim as my invention is:—

1. A combined sash holder and lock comprising a frame, a shaft rotatable therein, a pair of spaced apart cams fast on said shaft, an arm slideable in said frame and having one 45 end provided with a slot that loosely surrounds one of said cams, sash holding fingers carried by the other end of said arm, a second arm slideable in said frame and having a slotted end that surrounds the other 50 cam, and locking fingers carried by the other end of said last mentioned arm.

2. A combined sash holder and lock comprising a frame having an end plate, said plate provided with spaced apart slots, a 55 sash locking arm slideable in said frame and having fingers at one end that project through said slots, a sash holding arm also slideable in said frame and provided with an

end plate, fingers pivotally connected to said plate, and projecting through said slots, and means for independently actuating said locking and holding arms.

3. A combined sash holder and lock comprising a frame, a shaft rotatable therein, a pair of cams fast thereon and arranged at different angles, a sash holding arm slideable in said frame and engaging one of said cams, oppositely projecting holding fingers carried by said arm, a sash locking arm also slideable in said frame and engaging the other cam, and locking fingers projecting from said locking arm.

4. A combined sash holder and lock comprising a frame, an arm slideable therein, a pair of oppositely projecting spring pressed holding fingers pivoted to said arm, a second arm also slideable in said frame, a pair of locking fingers carried by said last mentioned arm, and means for independently actuating said arms.

5. In a device of the character described the combination of sash racks having inclined teeth and laterally projecting spaced apart side catches, and holding and locking fingers adapted for engagement with said teeth and catches respectively.

6. A sash rack comprising inclined rack teeth, and laterally projecting spaced apart side catches.

7. A combined sash holder and lock comprising a frame having a front plate, said plate provided with slots, a shaft mounted in the said frame and provided with a hand grip, a pair of oppositely projecting cams carried by said shaft, a sash holding arm slideable in said frame and having one end engaging one of said cams, a pair of spaced apart parallel locking fingers projecting from the opposite end of said arm and adapted to be projected through the slots of said frame plate, a second arm slideable in said frame and having one end engaging the other cam and its opposite end projecting between said locking fingers and provided with a plate, and holding fingers pivotally connected to said last mentioned plate and adapted to be projected through the slots of the frame plate.

In testimony whereof I affix my signature in presence of two witnesses.
